LAMP HOLDER

William R. Young, Fairfield, and Frank D. Bryant,
Stratford, Conn., assignors to General Electric
Company, a corporation of New York

Application May 12, 1939, Serial No. 273,256

2 Claims. (Cl. 173—354)

This invention relates to lamp holders for incandescent lamps, and more particularly to lamp holders provided with switch mechanism for controlling the supply of current to the lamp.

The object of the invention is to provide an improved construction and arrangement in lamp holders of the type described in which the switch mechanism is of simplified and rugged construction which may be easily assembled and manufactured at low cost.

In the accompanying drawing, Fig. 1 is an elevational view of the lamp holder; Fig. 2 is a view of the interior of the lamp holder showing the switch mechanism; Fig. 3 is another view of the interior of the lamp holder with a portion of the switch mechanism removed; Fig. 4 is a sectional view through the lamp holder along the line 4—4 of Fig. 3; Fig. 5 is another sectional view through the lamp holder along the line 5—5 of Fig. 3; Fig. 6 is an exploded view showing the elements of the switch mechanism; and Figs. 7 to 10, inclusive, are diagrammatic views showing the different positions of the switch mechanism in controlling an electric current to the lamp holder.

Referring to the drawing, the lamp holder is provided with a cylindrical housing 10 formed with an annular shoulder 11 on the interior wall thereof to receive a supporting member or base 12. The base conforms to the configuration of the housing and rests upon the shoulder 11 in which position it is held by fastening means such as screws 13, as shown by Fig. 1. A cover 14 closes one end of the housing. The elements thus far described are made of insulating material, for example, a phenolic condensation product and filler. The base 12 supports a switch mechanism on one side and a lamp socket means on the other side.

The lamp socket means is supported from the lower side of the base member and includes a screw shell receptacle 15, an intermediate contact member 16 and a center contact member 17. By this construction the lamp socket is adapted to receive a two-filament lamp but manifestly the socket may be adapted to receive a single filament lamp by omitting one of the contact members, usually the intermediate contact member. The screw shell is mounted on the base by screws 18 and 19 passing through ears 20 formed integrally with the shell and which are bent over to engage the face of the base member 12. In order to support the intermediate contact member 16, the base member is formed with an integral annular flange 21

depending from the lower face thereof and forming a recess 22. The intermediate contact member is shaped as an annulus and rests upon the surface of the flange, the latter forming a bearing surface for the contact member, a tang or projection 23 is formed integrally with the annulus and is secured to the base by a screw 24 to hold the contact member in position. The center contact member comprises a flat spring strip secured at one end to the base 12 by a screw 25 and the other end extends through a slot 26 in the flange 21 to a point at the center of the annular intermediate contact member within the recess 22. In this manner, the center and intermediate contact members are insulated from one another. A coiled spring 27 bears at one end against the center contact and at the other end against the base of the recess to resist deflection of the contact member upon engagement with the base of a lamp thereby maintaining good electrical contact with the base of the lamp.

The switch mechanism includes stationary contacts located on the upper side of the base 12 and electrically connected to the lamp socket means. As shown most clearly by Fig. 6, the upper face of the base is provided with an annular series of cam surfaces 28, 29, 30 and 31 forming adjacent hills and valleys for receiving the movable contacts, to be described hereinafter. Each of the cam surfaces 29, 30 and 31 is formed with a slotted or recessed portion to receive corresponding contacts 32, 33 and 34. The hill portions of the cam surfaces separate the contacts from one another. Each of the contacts is formed with a valley portion corresponding to and mating with the corresponding valley of the cam surface so that a continuous cam surface having alternate hills and valleys is formed by the contacts and cam surfaces 28. The assembled arrangement of these elements is shown by Fig. 3. The contact 32 is provided with an integral extension or terminal 35 fitting within a recess 36 formed in the base 12 and secured to the base by means of a screw 37. In order to provide for the connection of an electrical conductor, a terminal screw 38 is mounted on the extension 35. The contact 33 is formed with an integral arm 39 curving around the side 50 of the adjacent cam surface and an extension 40 resting in a recess 41 provided in the face of the base. The extension is formed with an opening 42 for receiving the screw 25 which holds the center contact 17 on the base. In this manner the contact 33 is electrically connected to the

center lamp contact 17. The contact 34 is provided with an integral extension 43 fitting within a recess 44 in the face of the base. An opening 45 is formed in the extension for receiving the screw 24 which holds the intermediate lamp contact in position on the base. In this manner the contact 34 is connected electrically to the intermediate contact of the lamp socket. A terminal member 46 is seated within a recess 47 in the base and is provided with a terminal screw 48 for receiving an electrical conductor. An opening 49 in the terminal member receives the screw 19 which holds the socket shell in position on the base. In this manner the terminal member 46 is connected electrically to the threaded shell 15 of the lamp socket means.

The switch mechanism also includes movable contact means cooperating with the fixed contacts. As shown most clearly by Figs 4 and 6, the upper face of the base 12 is formed with a bearing surface 50 which supports a rotatable element 51 of insulating material secured in position by a bolt 52. The rotatable element is of substantially circular shape and is provided around its outer periphery with a series of cam faces forming teeth in the ratchet wheel corresponding to the number of valleys designated by the fixed contacts and the cam face 28, in this case, four. A series of recesses or slots 54, 55, 56 and 57 are arranged in annular formation in the rotatable element adjacent the outer periphery thereof. The recesses 54, 55 and 56 extend into a groove 58 which receives a metallic shorting member 59. In this manner, one end of each of the recesses 54, 55 and 56 is closed by the shorting member while the corresponding end of the recess 57 is closed by the face of the rotatable element inasmuch as the latter recess does not extend through the member. The movable contacts are formed of ball bearings 60, 61, 62 and 63 which are disposed within the recesses 54, 55, 56 and 57, respectively. A coiled spring 64 is disposed between each of the ball bearings and the closed end of the respective recess. This means that the roller contacts or ball bearings 60, 61 and 62 are electrically interconnected by the shorting plate or member 59 and form live contacts in the circuit of the switch while the ball bearing 63 is seated within the recess 57 in the insulating rotatable member and constitutes a dead contact in the switch. The purpose of the ball bearing 63 is to provide another bearing surface supplementing the live contact ball bearings so that the ratchet wheel rotates freely and easily about the pin 53 without tilting out of position. The springs 64 maintain the ball bearings firmly in engagement with the fixed contact members to secure an effective electrical contact; at the same time, they permit the ball bearings to move longitudinally of the recesses as the ratchet wheel is rotated so that the ball bearings will easily pass over the hills separating the valleys in the fixed contact members. As shown most clearly by Fig. 4, a plate 65 of insulating material covers the shorting member 59 and is held in position by engagement with the head of the screw 52, the body of the screw passing through an opening 66 in the plate. While the movable switch contacts have been shown and described as ball bearings, it should be manifest that other forms of rotatable contacts may be employed, for example, cylindrical members.

The switch mechanism further includes operating means for the movable contacts. An op-

erating member or pawl 67 is secured to one end of a bead chain 68 which end, in turn, is fastened to a spring 69 attached to the base 12 by a pin or screw 70. As shown by Fig. 2, the spring, pawl and chain are disposed around the outer periphery of the ratchet wheel with the pawl in engagement with one of the teeth 53 and with the end of the chain passing through a guide 71 to the outside of the housing of the lamp holder. Rotation of the ratchet wheel is limited by enlarged beads formed in the bead chain 68; the enlarged bead 72 limits the counterclockwise rotation of the ratchet wheel, as shown in Fig. 2, and thereby the extension of the spring 69, while the enlarged bead 73 limits the clockwise rotation of the ratchet wheel and the retraction of the spring 69. In each case the enlarged bead engages the respective wall of the guide 71. The degree of angular movement of the rotatable member or ratchet wheel is, of course, limited and defined by the portions of the valleys in the fixed contact members. The tension in the spring normally maintains the bead chain and pawl in close engagement with the outer periphery of the rotatable member so that the pawl firmly engages the respective cam face 53. Upon pull of the chain 68 the pawl engages one of the cam surfaces and moves the rotatable member counterclockwise against the action of the spring until the ball bearings move over the hills into the adjoining valleys in the fixed contact members, at which point the enlarged bead abuts the guide 71 limiting movement of the chain. Upon release of the chain the spring 69 retracts the pawl into engagement with the next succeeding cam face 53 pulling the chain within the housing of the lamp holder until the enlarged bead 73 engages the guide 71.

In the use of the device the conducting wires L₁—L₂ of an electric power system are connected to the terminals 46 and 35, respectively, the wires passing through openings 74 in the cover 14, and a two-filament lamp is threaded into the screw shell 15 so that the lamp terminals engage the intermediate and outer contacts 16 and 17. When the switch mechanism is moved to the position shown diagrammatically by Fig. 7, one of the lamp filaments is energized. Current flows from line L₁ through terminal 46, screw 19, socket shell 15, the lamp filament, intermediate contact 16, screw 24, fixed contact 34, one of the ball bearing contacts and spring, shorting member 59, another of the ball bearing contacts and springs, contact 32 having the integral terminal 35 to the other power line L₂. In order to light the other filament of the lamp, the bead chain is pulled to move the switch mechanism to the position shown by Fig. 8. Current from the power line L₁ flows from the terminal through the screw shell in the manner just described to the other filament of the lamp and thence through the center contact 17, screw 25, fixed contact 33, the shorting member and appropriate ball bearings, contact 32 to the other power line L₂. When the switch mechanism is moved to the position shown by Fig. 9 both filaments of the lamp are energized in the manner described inasmuch as the shorting member and appropriate ball bearings are in electrical contact with all three of the fixed contacts. In order to turn off the lamp the switch mechanism is moved to the position shown by Fig. 10, so that the power line L₂ is disconnected from the circuit through the lamp holder.

The elements of the lamp holder may be easily

assembled by mounting the lamp socket structure and switch mechanism on the base 12 and then slipping the base into the shell 16. After assembling the base and shell the cover 14 is placed in position and secured to the shell by 5 bolts 75 passing through openings 76 in the base member. The switch mechanism gives a quick make and break of the circuits since as soon as the ball bearings pass the crests of the hills on the cam surfaces of the insulating base member 12 the springs force them downwardly into engagement with the adjoining contacts.

What we claim as new and desire to secure by Letters Patent of the United States is:

1. In a lamp holder, a supporting base of insulating material, lamp socket means mounted on one side of said base, a plurality of stationary contacts mounted on the other side of said base and being electrically connected to said socket means, a member rotatably mounted on said base 15 having a plurality of recesses therein and provided with an annular periphery having cam surfaces thereon, a ball bearing disposed in one end of each of said recesses, a shorting member carried by said rotatable member and overlying the other end of each of said recesses, spring means 20 in each of said recesses engaging said shorting

member and respective ball bearing and biasing said ball bearing into engagement with a stationary contact, and means for rotating said rotatable member, said means including an operating element engaging any one of said cam surfaces.

2. In a lamp holder, a supporting base of insulating material, lamp socket means mounted on one side of said base, a plurality of stationary contacts mounted on the other side of said base and being electrically connected to said socket means, a member rotatably mounted on said base having a plurality of recesses therein and provided with an annular periphery having cam surfaces thereon, a ball bearing disposed in one end of each of said recesses, a shorting member carried by said rotatable member and overlying the other end of each of said recesses, a plate of insulating material overlying said shorting member, spring means in each of said recesses engaging said shorting member and respective ball bearing and biasing said ball bearing into engagement with a stationary contact, and means including an operating element engaging said cam surfaces 25 for rotating said rotatable member.
